SMOKING PIPE CLEANER AND HOLDER

George W. Colby, Springfield, Vt.

Application March 29, 1955, Serial No. 497,562

4 Claims. (Cl. 131—232)

This invention relates to smoking pipe cleaners, and 15 holders, and more particularly to a device providing means for depositing a pipe and its ashes after a smoker is through with the pipe.

One object of the invention is to provide a container to catch and contain pipe residue, with a means for 20 emptying the container.

A further object is to provide means to hold the pipe firmly until it is to be used again, and without scratching the surface of the pipe.

A further object is to provide means for removing the residue from the inside of the pipe bowl, without 25 attention or effort on the part of the user.

A further object is to do the cleaning by means of the movement of the object to which the device is attached, as, for example, the dash of an automobile.

A further object is to accommodate as many types 30 and sizes of pipes, as is possible.

Further objects, purposes, and characteristic features will appear, as the description progresses, reference being made to the accompanying drawings, showing, by way of example, and in no way, in a limiting sense, two forms which the invention can assume.

In the drawings:

Figure 1 is a front elevational view of a device in accordance with this invention, as mounted on the dash 40 board of an automobile;

Figure 2 is a sectional view, on line 2—2 of Figure 1, and viewed in the direction of the arrows;

Figure 3 is a sectional view, on line 3—3 of Figure 2, and viewed in the direction of the arrows;

Figure 4 is a sectional view, on line 4—4 of Figure 3, and viewed in the direction of the arrows;

Figure 5 is a large scale, fragmentary elevational view of the device;

Figure 6 is a sectional view, on line 6—6 of Figure 2, 50 and viewed in the direction of the arrows;

Figure 7 is a side elevation of a modified form of the device, wherein the device rests on a table top.

Referring now to the drawings, and first to Figures 1—6, there is shown a lead pendulum bob 8, attached to the lower end 9, of a wire shaft 10. At the upper end 55 of the pendulum shaft, is carried a cleaning element comprising four steel fins 11, having a thin cross section, and positioned at right angles to each other.

At a point below the cleaning element, a pivot washer 12, and retaining washer 13, are provided to mount the pendulum assembly in a mounting plate 14, which has its center bulged upwardly and circularly, at 15, and is pierced to receive shaft 10. Pivot washer 12 thus rests on a circular line bearing on plate 14, so that the pendulum assembly can freely rotate, and swing, in any horizontal direction.

Mounting plate 14, is hung on four coil springs 16, anchored to a container top 17, as at 18. The domed 70 mounting plate 14 sleeved on the pendulum shaft 10, the pivot washer 12 fixed on the pendulum shaft 10 and bearing on top of the domed portion of the plate

2

14 and the coil spring 16 anchored to the container top 17 and to the mounting plate 14 constitute a universal movement support pivot mounting the pendulum shaft at a point below the cleaning head and permitting the pendulum shaft to move in three directions at right angles to each other.

Top 17 provided with an aperture 17' fits on a container 19, in which the lower part of the pendulum assembly is received, the cleaning element projecting up 10 through the top, to the outside.

Fastened to top 17, is a pipe clip 20, in the form of a curved steel spring, and is covered with rubber sleeves 21, to protect the finish on the pipe.

Also in top 17, is a sponge rubber ring 22 which extends about the aperture 17' in the top 17 and receives the open end of the bowl of a pipe 23. Attached firmly to top 17, is a bracket 24, and this bracket, in turn, is connected to a bracket 25, by means of a clamp screw 26 and a spacing sleeve 27, so that, when adjusted to the proper angle, to the dash 28 of an automobile, it can be locked, by lock nut 29. Suction cups 30, are provided on bracket 25, to hold the entire assembly, to the dash 28.

Thus, when pipe 23 is inserted into the cleaner, it is 25 gripped, on the stem by clip 20, and by the ring 22, which presses downwardly and conforms to the contour of the pipe bowl. The cleaning fins 11, are forced downward by the residue in the pipe bowl, thus putting springs 16 under tension. As the automobile moves, 30 pendulum 8 follows an erratic path, causing the cleaning element 11, to cut it way upward, and from side to side, through the residue, until it comes to rest on the inside bottom of the pipe bowl.

The residue falls, at 30, to the bottom of container 19, which can readily be removed from its top, 17, and emptied.

In Figure 7 is shown a slightly modified form of the invention. Here, the container 19a, is mounted on a base 31, with feet 32, and rests on a table top 33. In this case the energy for cleaning, is supplied by shaking container 19a, or otherwise moving pendulum 8, by hand.

The above rather specific description, of two forms which the invention can assume, has been given by way of example, and not, in any manner, whatsoever, in a limiting sense.

All modifications, alterations, and adaptations, such as fall within the scope of the appended claims, are intended to be covered by this disclosure.

What is claimed is:

1. A cleaner and holder for smoking pipes, comprising, in combination, a pendulum shaft, a pendulum bob fixed to the lower end of the shaft, a pipe bowl cleaning head connected to the upper end of the shaft, and a universal movement support pivot mounting the pendulum shaft at a point below the cleaning head and permitting the pendulum shaft to move in three directions at right angles to each other, an open ended container surrounding the pendulum shaft, a removable apertured top for closing the open end of the container, the cleaning head projecting up through the aperture in the top, the support pivot including a carrying plate sleeved on the shaft, a domed-up circular central portion on the plate and surrounding the shaft, a washer fixed on the shaft and bearing on the top of the domed portion, and a plurality of coil springs, each connected, at one end to the carrying plate, and at the other end, to said top, for floatingly supporting the shaft.

2. A cleaner and holder for smoking pipes, comprising, in combination, a pendulum shaft, a pendulum bob fixed to the lower end of the shaft, a pipe bowl cleaning head connected to the upper end of the shaft, and a

universal movement support pivot mounting the pendulum shaft at a point below the cleaning head and permitting the pendulum shaft to move in three directions at right angles to each other, an open ended container surrounding the pendulum shaft, a removable aperture 10 top for closing the open end of the container, the cleaning head projecting up through the aperture in the top, a spring clip bracket on the top for gripping the stem of a smoking pipe, and a flexible, non-abrasive ring surrounding the aperture in the top and adapted to embrace the open end of the bowl of a pipe held in said clip and with the bowl slipped over the cleaning head.

3. A cleaner and holder for smoking pipes, comprising, in combination, a pendulum shaft, a pendulum bob fixed to the lower end of the shaft, a pipe bowl cleaning head connected to the upper end of the shaft, and a universal movement support pivot mounting the pendulum shaft at a point below the cleaning head and permitting the pendulum shaft to move in three directions at right angles to each other, an open ended container surrounding the pendulum shaft, a removable apertured top for closing the open end of the container, the cleaning head projecting up through the aperture in the top, the support pivot including a carrying plate sleeved on the shaft, a domed-up circular central portion on the plate and surrounding the shaft, a washer fixed on the shaft and bearing on the top of the domed portion, and a plurality of coil springs, each connected, at one end to the carrying plate, and at the other end, to said top 30 for floatingly supporting the shaft, a spring clip bracket on the top for gripping the stem of a smoking pipe, and a sponge rubber ring surrounding the aperture in the top and adapted to embrace the open end of the bowl of a pipe held in said clip and with the bowl cupped over the top and adapted to embrace the open end of the bowl

of a pipe held in said clip and with the bowl cupped over the cleaning head.

4. A cleaner and holder for smoking pipes, comprising, in combination, a pendulum shaft, a pendulum bob fixed to the lower end of the shaft, a pipe bowl cleaning head connected to the upper end of the shaft, and a universal movement support pivot mounting the pendulum shaft at a point below the cleaning head and permitting the pendulum shaft to move in three directions at right angles to each other, an open ended container surrounding the pendulum shaft, a removable apertured top for closing the open end of the container, the cleaning head projecting up through the aperture in the top, the support pivot including a carrying plate sleeved on the shaft, a domed-up circular central portion on the plate and surrounding the shaft, a washer fixed on the shaft and bearing on the top of the domed portion, and a plurality of coil springs, each connected, at one end to the carrying plate, and at the other end, to said top 20 for floatingly supporting the shaft, a spring clip bracket on the top for gripping the stem of a smoking pipe, a sponge rubber ring surrounding the aperture in the top and adapted to embrace the open end of the bowl of a pipe held in said clip and with the bowl cupped over the top and adapted to embrace the open end of the bowl.
